UNITED STATES PATENT OFFICE.

OLIVER S. GARRETSON, OF BUFFALO, NEW YORK.

SLAG-FURNACE.

SPECIFICATION forming part of Letters Patent No. 728,794, dated May 19, 1903.

Application filed March 18, 1902. Serial No. 98,719. (No model.)

To all whom it may concern:

Be it known that I, OLIVER S. GARRETSON, a citizen of the United States, and a resident of Buffalo, in the county of Erie and State of New York, have invented a new and useful Improvement in Slag-Furnaces, of which the following is a specification.

This invention relates to an apparatus of the same general nature as that disclosed in my application for United States patent, Serial No. 98,159, filed March 14, 1902, and which is intended for utilizing the heat contained in molten slag to heat air by partially cooling the slag to the point at which it is congealed and non-adhesive, while still containing the bulk of its heat, and piling this hot slag in the form of small pieces or fragments in a chamber or pit, through which the air is caused to flow which is to be heated.

The present invention is directed to a particular mechanism for partially cooling and congealing the slag; and its object is to provide a simple and durable mechanism consisting of a rotary drum or wheel for forming or molding the slag into small pigs, bars, or pieces, which can be piled or heaped in the slag-chamber in a loose mass having numerous interstices, through which the air can be readily circulated, and whereby a large heating-surface of congealed slag is presented to the air.

In the accompanying drawings, consisting of three sheets, Figure 1 is a longitudinal sectional elevation through an apparatus embodying the invention in line 1 1, Fig. 2. Fig. 2 is a transverse sectional elevation through the apparatus in line 2 2, Fig. 1. Fig. 3 is a top plan view on a reduced scale. Fig. 4 is a longitudinal section through the slag-wheel on an enlarged scale. Fig. 5 is a transverse sectional elevation through the slag-wheel in line 5 5, Fig. 4.

Like letters of reference refer to like parts in the several figures.

The apparatus shown in the drawings illustrates the application of the invention to a steam-boiler.

A represents the boiler-furnace, which is provided with a grate *a* or other suitable means for burning fuel, a combustion-chamber *a'*, and a draft-passage *a''*, which communicates at its rear end with the smoke-flue

B, provided with a damper *b*. The boiler shown in the drawings is of the Babcock & Wilcox type, having an upper drum C and lower inclined water-tubes C'. The products of combustion pass from the combustion-chamber over the bridge-wall *d*, downwardly in rear of the latter and in front of the baffle-wall *d'*, and upwardly in rear of the latter to the smoke-flue B. A furnace and boiler of any other form, construction, and arrangement may, however, be employed, or instead of heating a boiler the invention may be employed for heating some other apparatus.

E represents a slag chamber or pit which is preferably arranged below the level of the steam-boiler furnace and to one side thereof, as indicated in Fig. 1. This slag-chamber communicates at its upper end with the combustion-chamber of the boiler-furnace by a passage *e*. The lower end of the slag pit or chamber is preferably contracted, as indicated at *e'*, and is provided with a discharge-opening *e''* for the cooled slag. The slag-chamber is provided in its walls near its lower end, preferably above the contracted portion, with ports *f*, which communicate with a horizontal flue F, surrounding the lower portion of the slag-chamber. This flue F communicates with a vertical return flue or passage G, which connects by a horizontal passage *g* with the lower end of a passage *g'*, opening into the rear portion of the draft-passage of the boiler-furnace.

H represents a fan or blower, which may be of any suitable type and arranged at any suitable point to cause the air to circulate through the slag-chamber, the boiler, and the return flues or passages. In the construction shown the fan is located at the mouth of the passage *g'* and operates to move the air up through the slag chamber or pit, through the boiler flues or passages, and down through the return flues or passages *g', g, G*, and F and ports *f* to the lower portion of the slag-chamber.

I represents a conveyer of any suitable construction arranged below the discharge-opening *e''* of the slag-chamber to receive the cooled slag discharged through the same and carry it off to a desired point.

Before introducing the slag into the slag chamber or pit it is partially cooled and

formed into small pigs, bars, or pieces, which when dropped into the slag chamber or pit will pile or heap indiscriminately and form a loose mass having numerous interstices, through which the air can be freely circulated. The mechanism shown in the drawings for this purpose and forming the subject-matter of this application is constructed as follows: J represents a rotary slag drum or wheel which is provided in its peripheral face with molds, depressions, or pockets, into which the molten slag is received on the upper side of the wheel and in which the slag becomes partially cooled and congealed as the wheel slowly rotates and from which the pigs, bars, or pieces of partially-cooled slag are delivered on the lower side of the drum or wheel into the slag-chamber. This slag drum or wheel is rotatably mounted above the slag-chamber in a covered compartment, which may be an enlargement of the slag-chamber. The slag-wheel (shown most clearly in Figs. 4 and 5) is provided with a hollow hub j, provided with hollow trunnions which are journaled in bearings j', supported in any suitable manner—for instance, by beams j"—in the wheel-compartment. The wheel is provided with hollow spokes j", each of which communicates with the hollow hub and with a rim composed of a series of hollow sections j³. The hollow rim-sections are preferably detachably connected to the spokes or rim-supports j" by bolts or otherwise and are formed of copper or other metal of considerable conductivity of heat and which is not easily corroded or affected by the molten slag. The rim-sections form a continuous circulator-rim, the peripheral face of which is provided with an annular series of small pockets, molds, or depressions K for receiving the molten slag.

The molten slag is fed by any suitable means against the face of the drum or wheel, at the upper side thereof, so that the slag molds or pockets successively receive the slag as they are brought by the rotation of the wheel to a position in which the molten slag can flow into the same. In the drawings a hopper or wide funnel L is shown for that purpose in the upper portion of the compartment in which the slag-wheel is mounted. This hopper is provided at one side of its bottom opening with a flange which fits tightly against the peripheral face of the slag-wheel and prevents the escape of the slag from the hopper except into the pockets or molds of the wheel. The molten slag is supplied to the hopper by a slag-spout l or the like from the metallurgical furnace. As the slag pockets or molds are carried beneath the open bottom of the hopper the molten slag flows from the latter into the pockets or molds and fills the same.

M represents a segmental hollow shield which extends from the rear side of the hopper around the rear side of the wheel to a point beneath the latter. The wheel rotates slowly

about its axis in the direction of the arrow, Fig. 4, and the filled slag pockets or molds are thereby carried from the upper to the lower side of the wheel. The segmental shield prevents the slag from escaping from the pockets or molds until the latter are carried past the lower end of the shield, when the pigs, bars, or pieces of slag which have congealed during the time that they have been held in the pockets fall from the same into the slag-chamber or pit. The pigs or pieces of slag pile up in the slag-chamber or pit in a loose heap or mass, through the interstices of which air can be readily circulated. The slag-wheel is slowly rotated by any suitable mechanism, preferably by a worm-wheel Q, which is secured to one of the wheel-trunnions and with which meshes a worm q, secured on a shaft q', journaled in bearings q² in the wheel-chamber and provided with a driving sprocket-wheel or the like q³. The one-sided or overhanging weight of the slag on the wheel may be utilized for rotating the wheel, in which case the described worm mechanism serves to regulate the speed.

The slag-wheel and the shield are made hollow, so that a cooling medium, such as water, can be circulated through the same to prevent the slag from burning them and for quickening the congealing process.

R represents a water-pipe which is provided with a branch r, entering one of the hollow trunnions of the wheel, and with a branch r', leading to the lower portion of the hollow shield.

r² r³ represent exit-pipes leading, respectively, from the opposite trunnion of the wheel and from the upper portion of the hollow shield. Sufficient water is supplied to the wheel to keep the hollow spokes and rim-sections at the lower half of the wheel filled. The hollow rim-sections are thus cooled before they move upwardly to the slag-hopper and are sufficiently cool to prevent the slag from burning the peripheral portion of the wheel. The rim is preferably made of heavy copper, which metal has a great capacity for carrying off heat. When the slag-wheel is arranged in a compartment communicating with the slag chamber or pit, as shown, the heat radiated from the slag on the wheel aids in heating the air passing through the slag-chamber.

The operation of the apparatus is as follows: The molten slag is spouted into the feed-hopper L, from which it flows into the slag pockets or molds of the wheel. The slag is retained in these pockets or molds sufficiently long to become solid, so that when it drops from the pockets or molds at the lower side of the wheel into the slag chamber or pit the slag is solid and non-adhesive and forms a loose heap or mass. When first starting the apparatus and until the slag reaches a sufficient height in the pit or chamber, the furnace can be operated by a fire built on the grate a. While the fire is burning on the

grate the damper *b* in the smoke-flue *B* is open, and the products of combustion pass from the combustion-chamber through the boiler-passages and out through the smoke-flue. When sufficient slag has accumulated in the slag chamber or pit to heat the boiler, the damper is closed and the fire permitted to die. The fan *H* is then started and the air, as indicated by the arrows, is drawn up through the slag chamber or pit and the slag therein, thence through the boiler-passages and into the return-passages, which connect with the ports *f* in the lower portion of the slag chamber or pit. The circulation is continuous and forms an endless air-belt, in which the hot air from the slag chamber or pit passes to the boiler to heat the latter, and after it has given up more or less of its heat to the boiler is returned to the slag-chamber to be reheated. The cooling slag is removed from the lower end of the chamber or pit from time to time by the conveyer *I*. The water, which becomes heated by passing through the slag-wheel, can be used for feeding the boiler or for other purposes.

I claim as my invention—

1. The combination of a rotary slag wheel or drum provided in its peripheral face with molds or pockets for receiving the molten slag, said wheel or drum consisting of a hollow hub, hollow spokes radiating from said hub, and a rim composed of hollow separable sections detachably connected together and to said spokes, and means for causing a cooling agent to flow through said hollow hub, spokes and rim-sections, substantially as set forth.
2. The combination of a rotary slag wheel or drum provided with molds or pockets for receiving molten slag, means for cooling said wheel, and a segmental shield which confines the slag in the molds or pockets during part of the rotation of the wheel, substantially as set forth.
3. The combination of a hollow, rotary slag wheel or drum provided with molds or pockets for receiving molten slag, means for causing a cooling agent to flow through said wheel, and a segmental shield which confines the slag in the molds or pockets during part of the rotation of the wheel, substantially as set forth.
4. The combination of a hollow wheel or drum provided with molds or pockets for receiving molten slag, means for causing a

cooling agent to flow through said wheel, a hollow segmental shield which confines the slag in the molds or pockets during a part of a rotation of the wheel, and means for causing a cooling agent to flow through said hollow shield, substantially as set forth.

5. The combination of a slag-chamber, means for circulating air through the same, a rotary slag-wheel provided with molds or pockets for receiving and congealing the molten slag, and a segmental shield for confining the slag in said molds or pockets until congealed and discharging the congealed slag into said slag-chamber, substantially as set forth.

6. The combination of a slag-chamber, means for circulating air through the same, a rotary slag-wheel provided with peripheral slag molds or pockets which are inverted by the rotary movement of the wheel to discharge the congealed slag into said slag-chamber, means for supplying molten slag to said molds or pockets above the axis of rotation of the wheel, and a segmental shield for retaining the slag in said molds or pockets for a part of the rotation of the wheel, substantially as set forth.

7. The combination of a slag-chamber, means for circulating air through the same, a rotary slag-wheel provided with peripheral slag molds or pockets which are inverted by the rotary movement of the wheel to discharge the congealed slag, a hopper for supplying molten slag to said receivers at a point above the axis of rotation of said wheel, and a segmental shield which surrounds a portion of said wheel and prevents the congealed slag from discharging from said molds or pockets until the same pass the end of the shield, substantially as set forth.

8. The combination of a slag-chamber, means for circulating air through the same, a rotary, hollow slag-wheel provided with molds or pockets for receiving and congealing the molten slag, a segmental hollow shield surrounding a portion of said wheel, and means for supplying a cooling medium to said hollow wheel and to said hollow shield, substantially as set forth.

Witness my hand this 10th day of March, 1902.

OLIVER S. GARRETSON.
